BROAD BAND ANTENNA

Douglas W. Wilson and Ralph E. Taylor,
Washington, D. C.

Application October 16, 1945, Serial No. 622,660

4 Claims. (Cl. 250—33)

(Granted under the act of March 3, 1883, as
amended April 30, 1928; 370 O. G. 757)

1

This invention relates to wide-band antennas. An object of the invention is to provide an antenna which terminates a transmission line in an impedance producing a small reflection over a wide frequency band.

Another object of the invention is to provide a novel antenna operating efficiently over a wide frequency band.

Other objects, features, and advantages of the invention will be apparent from the following description and the accompanying drawing, in which:

Fig. 1 is a top view of an exemplary embodiment of an antenna in accordance with the invention, and

Fig. 2 is a cross-sectional view of the embodiment shown in Fig. 1, taken in the plane 2—2.

Referring now to the drawing, an antenna in accordance with the invention comprises a conical element 10, a section 14 of coaxial transmission line extending coaxially through the apex of the conical element 10, an extension 15 of the inner conductor of the transmission line beyond the end of the line section 14, and a plurality of electrically conductive rods 12, 13. The conical element 10 is constructed of electrically conductive material. The rods 12, 13 are also made of conductive material and may be of tubular or solid cross-section. The conical element 10 is conductively attached near its apex to the line section 14 in the plane of its intersection therewith. The rods 12, 13 preferably are positioned perpendicular to each other and to the line section 14 in order to minimize undesirable electrical coupling between each rod and the other components of the antenna.

In addition, insulators (not shown) may be incorporated in the antenna in order to provide adequate rigidity and strength without affecting appreciably the electrical characteristic of the antenna.

As shown in the drawing, the antenna may be energized by a radio frequency generator 16 coupled to the antenna by means of the transmission line 11. In order to effect efficient radiation of the power developed by the generator 16, it is necessary that the characteristic impedance of the line 11 match the antenna impedance measured at the lower end of the line section 14. A further requirement for the efficient radiation of energy is the elimination of radio frequency current on the exterior surface of the line 11.

The rods 12 and 13 terminate the outer surface of line section 14 near the apex of the conical element 10 in admittances which vary as the fre-

quency is changed. The variation of the admittances of the rods tends to compensate for the varying impedance of elements 14 and 15 so that the antenna terminates the line 11 with a reasonably constant impedance as the frequency is varied.

The rods 12, 13 may be constructed so that the lengths thereof may be readily adjustable. For example, a telescoping type of construction may be used.

10 The outer surfaces of the antenna components radiate the energy supplied to the antenna by the radio frequency generator 16. The line section 14 constitutes a transformer which matches the normally high but reasonably constant resistance 15 characteristic of the radiating portion of the antenna to the characteristic impedance of the line 11 and at the same time suppresses by cancellation the normally varying reactance characteristic of the radiating portion of the antenna.

20 The conical element 10 constitutes a broad band detuning device which preserves the unbalanced property of the coaxial transmission line 11 and thereby prevents radiation from the outer surface of the line 11.

25 The dimensions of an antenna according to the invention may be referred to the wavelength, λ , corresponding to the lower frequency limit of the band of frequencies over which efficient operation is desired. The dimensions indicated in the drawing are those of a model of the invention which proved to operate satisfactorily over a two to one frequency ratio. In the particular embodiment herein illustrated the extended portions 30 of conductor 14 and inner conductor 15 are each .11 λ long. Rods 12 and 13 are .11 λ and .15 λ long respectively and conical member 10 .13 λ long.

35 In a satisfactory model of the antenna, which 40 was designed to match a 50 chm transmission line, the optimum value of characteristic impedance of the line section 14 was found to be of the order of 125 chms. The optimum lengths of the rods 12, 13 may best be determined experimentally by adjusting the lengths of the rods individually to maintain a satisfactory impedance match between the line 11 and the antenna over the entire operating frequency band.

45 It will be understood that the invention is not 50 limited by the exemplary embodiment herein described and that the scope of the invention is to be determined by reference to the appended claims.

The invention described herein may be manufactured and used by or for the Government of

the United States of America for governmental purposes without the payment of any royalties thereon or therefor.

What is claimed is:

1. An antenna comprising a substantially conical element, a coaxial transmission line passing through the conical element coaxially therewith, the outer conductor of the line being conductively attached to the conical element in the plane of intersection therebetween, an extension of the outer conductor of the line beyond the plane of intersection with the conical element, said extension consisting of a cylindrical conductor equal to a fractional part of a quarter wavelength long at the low end of the frequency band to be covered and an extension of similar length of the inner conductor of the line beyond the end of the outer conductor.

2. An antenna comprising a substantially conical element, a coaxial transmission line passing through the conical element coaxially therewith, the outer conductor of the line being conductively attached to the conical element in the plane of intersection therebetween, an extension of the outer conductor of the line beyond the apex of the conical element, an extension of the inner conductor of the line beyond the end of the outer conductor, and a plurality of conductive rods conductively attached to the outer conductor and extending perpendicularly away therefrom in said plane of intersection.

3. An antenna comprising a substantially conical element, a coaxial transmission line passing through the conical element coaxially therewith, the outer conductor of the line being conductively attached to the conical element in the plane of intersection therebetween, an extension of the outer conductor of the line beyond the apex of the conical element, an extension of the inner

conductor of the line beyond the end of the outer conductor, and a plurality of conductive rods of unequal lengths conductively attached to the outer conductor and extending perpendicularly away therefrom in said plane of intersection.

4. An antenna comprising a substantially conical element, a coaxial transmission line passing through the conical element coaxially therewith, the outer conductor of said line being conductively attached to the conical element in the plane of intersection therebetween, an extension of the outer conductor of said line beyond the apex of the conical element, an extension of the inner conductor of said line beyond the end of the outer conductor, and a conducting surface extending at right angles to the outer conductor of said transmission line and attached thereto at the plane of intersection of said line and said conical element.
